UNITED STATES PATENT OFFICE.

ALFRED C. FUNK AND THOMAS E. TURNER, OF SPRINGFIELD, OHIO, ASSIGNORS TO
INTERNATIONAL HARVESTER COMPANY, A CORPORATION OF NEW JERSEY.

HAY-PRESS.

932,542.

Specification of Letters Patent. Patented Aug. 31, 1909.

Application filed March 1, 1909. Serial No. 480,774.

To all whom it may concern:

Be it known that we, ALFRED C. FUNK and THOMAS E. TURNER, citizens of the United States, residing at Springfield, in the county 5 of Clark and State of Ohio, have invented certain new and useful Improvements in Hay-Presses, of which the following is a specification.

Our invention relates to hay presses of the 10 rebounding plunger type, and in particular to the form of press in which the presser head is actuated by means of a draw bar connecting it with the power transmitting means.

15 It consists of means connected with the draw bar and operative in a manner to sustain the latter against excessive vibration during the operation of the machine; the object of our invention being to improve the 20 construction of the mechanism indicated for the purpose of making it stronger and more efficient in its operation. This result is attained by means of the mechanism illustrated in the drawing, in which—

25 Figure 1 is a top plan view of part of a hay press embodying our invention; Fig. 2 is an enlarged detail drawing representing a plan view of the swinging draw bar support; and Fig. 3 is a cross section of Fig. 2 30 along the line A—B.

The same reference characters designate like parts throughout the several views.

1 designates a part of the bed frame of the machine, 2 the draw bar, 3 a power transmitting arm having one end of the draw bar connected therewith, the opposite end of said bar being connected with the presser head operating means 3¹, 4 a power transmitting lever pivoted to the frame eccentric to said 35 arm and having rollers 5 adapted to contact with the arm during a part of the rotative movement of the lever in a manner to move the arm to actuate the draw bar in a direction to compress the charge, and 6 represents 40 a sweep lever attached thereto and to which power is applied in a well-known way.

45 In the operation of the machine the power transmitting arm 3 is vibrated about its axis as shown by dotted lines in Fig. 1, and when 50 moved in one direction the draw bar is pulled in a direction to compress the charge of hay, and when the presser head rebounds the arm 3 is moved rapidly in an opposite

direction, and when the limit of such movement is reached, contacts with a buffer 55 spring mechanism 7 in a manner to cushion the force of its return.

The above described mechanism is all of a well-known form and in extensive use, and such use has disclosed a defect in the operation of the machine, the removal of which is the primary object of our invention.

When the presser head rebounds and the draw bar is thrown rapidly toward the power transmitting means, the end connected with arm 3 moves in both a lateral and longitudinal direction, which movement causes a destructive vibration of the bar in the absence of some means for controlling such vibration. The means we have provided include a laterally projecting strap 8 secured to the upper side of the bed frame by means of bolts 9, and having its outer end forming a clevis 10 adapted to receive in a pivotal manner one end of a radius bar 11, 70 the opposite end of the bar being pivotally connected with the draw bar by means of clips 12 clamped to the bar by means of bolts 13. The bar swings from side to side of its pivotal connection with the strap 80 when the machine is in operation and effectively controls the vibration of the draw bar.

What we claim as our invention, and desire to secure by Letters Patent, is:

A hay press including, in combination, a 85 power transmitting arm, presser head operating means, a draw bar having one end connected with said presser head operating means and its opposite end with said power transmitting arm, a bed frame, a strap secured to said bed frame and projecting laterally therefrom, a radius bar having one end pivotally connected with the projecting end of said strap and its opposite end pivotally connected with said draw bar intermediate 90 its ends by means of clips clamped to said draw bar, said radius bar being adapted to swing from side to side of its pivotal connection with said strap in a manner to prevent an excessive vibration of said draw 95 bar.

ALFRED C. FUNK.
THOMAS E. TURNER.
